CLIFTON CHISHOLM, OF CLEVELAND, OHIO, ASSIGNOR TO THE AMERICAN MULTIGRAPH COMPANY, OF CLEVELAND, OHIO, A CORPORATION OF OHIO.

IMPRESSION MECHANISM FOR ADDRESSING MACHINES.

1,423,189.

Specification of Letters Patent. Patented July 18, 1922.

Application filed October 29, 1920. Serial No. 420,415.

To all whom it may concern:

Be it known that I, CLIFTON CHISHOLM, a citizen of the United States, residing at Cleveland, in the county of Cuyahoga and State of Ohio, have invented a certain new and useful Improvement in Impression Mechanism for Addressing Machines, of which the following is a full, clear, and exact description, reference being had to the accompanying drawings.

This invention relates to impression mechanism co-operative with address plates and paper to print as the plates and paper are mutually presented in an address printing machine.

One of the objects of the invention is to provide impression members or platens, which will operate efficiently with various sizes and forms of paper, printing the address without danger of smudging the surrounding regions of the paper.

Another feature is the provision for convenient and accurate adjustability of one of the platens, with reference to the other, to vary the force of impression.

The drawings illustrate the impressing mechanism in an approved form, the details of which are also included within my invention.

30 In the drawings Fig. 1 is a sectional elevation of the impression members and adjacent parts of an addressing machine; Fig. 2 is a cross section on the line 2—2 of Fig. 1, looking toward the right; Fig. 3 is a perspective of one of the platens arranged to act also as a paper feeding roller; Fig. 4 is a detail showing in plan the mechanism for effecting the pressure adjustment.

As shown in Fig. 1, 10 indicates a suitable bed plate, 11 a vertical plate or standard rising therefrom. Journalized in this plate and a corresponding member, not shown, is a shaft 12 on which is mounted the upper platen or paper feed drum 14. Below the shaft 12 is a revolvable shaft 15 mounted in the frame plates and carrying eccentrically a cylindrical sleeve 20, loose on the shaft. Surrounding this sleeve is the pressure platen, shown as composed of a cylindrical core 22 and a rubber surface 24. On the shaft 15 are a pair of sprocket wheels 30, which carry conveyer chains 31, having at intervals projections 32.

The rotation of the shaft 15 will advance 55 the conveyer chains to feed plates between

the two roller platens. The two shafts 15 and 12 rotate in timed relation, so that a certain portion or portions of the drum 14 comes successively into coaction with the plates brought into position by the conveyer chains. 60 The impression platen 24, however, rotates freely, and thus accommodates itself to any change in the relation between the paper drum and conveyer chain movements.

My prior application No. 371,722, filed 65 April 6, 1920, illustrates a change speed gearing wherein a paper feeding drum may make either a half or a whole rotation for such travel of the conveyer chain as brings an address plate into action, so that either two ordinary envelopes or one large envelope or sheet of paper may be fed for each rotation of the paper feeding drum. In the present invention the paper feed drum has two diametrically opposed platen surfaces and is 70 particularly well adapted for such change speed operation.

As shown particularly in Fig. 3, the paper platen comprises, beside the main drum member 14, a pair of rings or flanges 40 secured 80 to the sides thereof adjacent to the periphery, arcuate yielding strips 42 secured to the drum body adjacent to the rings (preferably by vulcanization) and yielding segmental members 41 removably mounted between 85 these rings and between the end of the strips. These segmental members are shown as comprising elastic inner and outer portions between which is the metallic plate 44 to which the elastic members, preferably of rubber, 90 are secured as by vulcanization. The inner elastic member 43 and the plate 42 preferably project beyond the outer member to provide a ledge at the edge. Suitable set screws 45 screw into the drum body with their heads overlapping such ledge, as shown in Figs. 1 and 3. By this means, the segmental member is retained in place but may be readily replaced when worn.

The outer surfaces of the platen members 100 41 and the strips 42 form a substantially continuous cylindrical surface of slightly greater radius than the rings 40. These strips and platen members co-operate with a pair of rollers 50 bearing against them to enable 105 sheets of paper or envelopes, which span the strips to be readily fed about the drum into printing position. Maintenance of the paper against the strips is assured by an arcuate shield 52 having openings 53 through which 110

the rollers project, and an arcuate shield strip 54 intermediate of the rollers and strips and lying close to the paper. The rollers 50 have their shafts slidably mounted in the frame plates, the rollers being pressed toward the drum by springs 55, which thrust against blocks 56 bearing on the shafts. The springs are adjusted by set screws 57 mounted in cap plates 58.

10 The described construction enables the sheet or envelopes to be fed with the drum to printing position. If only one impression is made for each rotation of the drum 14, one of the segmental blocks 41 is idle. If however, an impression is to be made twice for each rotation, each of the blocks acts as a platen, co-operating with the loose roller 24.

It is desirable to have in machines of this kind automatic means for throwing the mechanism out of operation in case paper is absent, and a convenient method is to have a light roller bear on the paper as it moves about the drum, such roller moving into a recess when the paper is absent, and thereby through suitable mechanism causing the operation of the throw-out. A satisfactory throw-out mechanism so initiated is shown in detail and claimed in my application No. 425,476 filed November 20, 1920. It is very convenient to provide the peripheral recesses for such throw-out roller by recessing the side of the rings 40 opposite the ends of the segment members. Such recessing is shown in Figs. 2 and 3 at 48. While this recess is in the nature of a rabbet the elastic member co-operates with the side wall of the ring to make the recess a groove, as clearly appears in Fig. 2.

To adjust the platen accurately, from a convenient location, to enable the proper impression, I provide mechanism shown in Figs. 1 and 4. Thus the sleeve 20 which is eccentrically mounted on the shaft 15, has secured to it an arm 60, which is connected by a link 61 with a rock arm 62 secured to a shaft 63. On this shaft is an operating rock arm 64. This arm has a projected end 65, in which is threaded a set screw 66. This set screw co-operates with a notched segment 68, which may be a plate secured to the bearing 69 for the shaft. By this arrangement the set screw holds the platen axis in desired position, but by loosening the set screw the arm 64 may be raised or lowered to turn the eccentric sleeve 20, and thereby adjust the platen impression.

It will be seen that the movement of the arm 64 from one notch to the next is a very small angular amount and the platen is accordingly adjustable by very fine increments.

Having thus described my invention, I claim:

1. In a mechanism of the character described, the combination with an impression

roller, of a coacting roller drum having on its surface a plurality of arcuate platen members, arcuate strips on the drum between said platen members, and feeding rollers bearing on the strips.

70

2. The combination with an impression roller, of a drum having a pair of edge rings and a pair of separated removable yielding arcuate platen members between the rings, the periphery of the rings being of less radius than the platen members.

75

3. The combination with an impression roller, of a drum having a pair of edge rings and a pair of separated arcuate yielding strips between and adjacent to the rings, and rollers pressed against the strips.

80

4. In a machine of the character described, a drum having edge rings projecting beyond the body of the drum, and a plurality of removable platen members resting on the body of the drum between the edge rings, and securing devices carried by the body of the drum for locking the platen members in place, arcuate strips on the body of the drum between the platen members, and rollers coacting with said strips.

85

5. In a machine of the character described, a drum having edge rings projecting beyond the body of the drum, and a plurality of platen members resting on the body of the drum between the edge rings, and securing devices carried by the body of the drum and overlapping ledges on the platen members.

90

6. In a machine of the character described, a drum having a body portion with projecting edges, an elastic platen member mounted on the body between the edges, said platen member having two elastic portions with an intermediate non-elastic portion, said non-elastic portion projecting at the edge, and locking devices carried by the drum and engaging said projecting portions.

95

7. The combination of a drum having a body and two edge rings, of a plurality of arcuate platen members mounted on the body between the edge rings, each platen member having two elastic portions between which is a metal portion, the metal portion projecting beyond the outer elastic portion, and screws threaded in the body, and having heads overhanging the projecting metal separator.

100

8. The combination of a drum having a body and edge members of greater diameter, platen members mounted on the body between the edge members, arcuate strips on the body between the edge members, rollers bearing against the arcuate strips, and a shield lying close to the edge members and having openings through which the rollers project.

105

9. The combination of a drum having a pair of edge flanges, an arcuate platen between the flanges, arcuate strips between the flanges, rollers bearing against the strips,

110

and a shield between the rollers and adapted to lie close to a sheet of paper bridging the strips.

10. The combination of a drum having a pair of peripheral yielding strips, rollers bearing against the strips, and a shield between the rollers and adapted to lie close to a sheet of paper bridging the strips, and another shield opposite the strips and having openings through which the rollers project.

11. The combination of a drum having edge flanges and peripheral strips between the flanges, an arcuate shield substantially concentric of the drum about the strips,

shafts extending parallel with the drum axis, separated rollers on said shafts extending through openings in the shield into engagement with the strips, said shafts lying behind said shield.

12. A paper feeding drum having a body portion, a pair of edge flanges and arcuate platen members between the edge flanges, one of said flanges being rabbeted opposite the platen member, whereby the platen member and the flange form a groove adapted to receive a paper feeler.

In testimony whereof, I hereunto affix my signature.

CLIFTON CHISHOLM.
